METHOD OF AND MACHINE FOR THE PRODUCTION OF SHEETS OF FLAT MATCHES

Jacob Brügger, Frutigen, Switzerland

Application February 15, 1932, Serial No. 593,157
In Switzerland February 20, 1931

18 Claims. (Cl. 144—50)

This invention relates to the production of sheets of flat matches and splints of which are connected to each other at one end.

In the known manufacture of sheets or cards of this kind, the cards which have been cut from wet wood are first trimmed and the matches are formed by stamping out their tips and severing them at their flanks to the required size, then the cards are successively subjected to the stamping, 5 impregnating and drying operations. With this sequence of working incidences, particularly, the outer matches of a card usually became unequal, as the wood remained moist until after the stamping operation, thus having time for warping.

10 The object of this invention is to avoid these disadvantages by taking the web of material obtained in a match-stock-cutting machine and feeding the same forward in the longitudinal direction and successively impregnating, drying 15 and stamping the sheets of matches therefrom.

This method permits of subjecting the material to the stamping operation in a dry condition, so that subsequent warping of the wood is rendered impossible and a series of sheets or cards for producing matches therefrom of uniform width throughout is obtained.

The machine for producing cards of flat matches, the splints of which are connected to each other at one end, by means of the method 20 according to the invention is provided with an impregnating device for the material for the matches and a drying device correlated thereto which is succeeded by a stamping device, the arrangement being such, that the material for 25 the matches passes through the impregnating device first and through the stamping device last.

The method according to the invention is hereinafter described by way of example only and by taking reference to the drawings in which 30 a constructional form of a machine for carrying out the method is illustrated.

In these drawings

Fig. 1 is a schematical elevation of a machine, and

45 Fig. 2 a corresponding plan view.

Fig. 3 shows the machine in a longitudinal section with its middle portion broken away,

Fig. 4 is a top plan view of the rear end of the machine,

50 Figs. 5, 6 and 7 show on a larger scale details of the conveying and dressing devices in a cross-section, a top plan view and a longitudinal section respectively,

Fig. 8 is a front view of the stamping device,

55 Fig. 9 is a longitudinal section of the stamping

device on the longitudinal axis of the machine taken as a whole,

Figs. 10 to 13 are views on a larger scale of details of the stamping tools including the cutting blades, and of the means for fastening as well as guiding and advancing the web of material,

Fig. 14 is a perspective view of a detail,

Figs. 15 and 16 illustrate two forms of stamped match cards,

60 Fig. 17 is a longitudinal section along the longitudinal axis of the machine taken as a whole of a first form of a stacking device for the match cards.

Fig. 18 is a front view of Fig. 17,

65 Fig. 19 shows a side elevation of the driving means,

Fig. 20 depicts a longitudinal elevation of a second constructional form of the stacking device,

70 Fig. 21 is a top plan view of Fig. 20, and

Fig. 22 illustrates a view of a detail on a larger scale.

75 Referring particularly to the Figs. 1 and 2 of the drawings, at the one end of the machine a winding device V for a web of material for the matches, for example of wood, is arranged, which is provided with a plurality, for instance twelve, individually rotatable supply rolls each to carry a web B of fresh, i. e. wet wood.

80 From the winding device the webs B pass over guide rolls through an impregnating tank J in which the webs are impregnated to the desired degree and eventually dyed a suitable color. After the impregnation the webs B travel on a conveyor band 6 through a drying chamber K, whereupon they enter in completely dry condition in a stamping device arranged in front of the drying chamber. During the passage through the drying chamber the webs are subjected to a 85 uniform longitudinal tensioning by means of a stretching device. This stretching device is composed of the pairs of rollers 1, 2 and 30, 31 respectively which are arranged at the entrance for the webs B in the drying chamber K as well as at the 90 exit for the same. The first-mentioned pair of feed rolls is driven from the conveyor band 6 in continuous manner and the latter in intermittent manner from the drive W of the stamping device. There is sufficient elasticity in the web of material itself to permit the resulting stretching effect. After leaving the stamping device the definitely stamped and severed match cards are received by a transfer device P in which a transmission drum 69 for conveying the match cards 95 100 105 110

- to trays R for stacking the same is provided, from which trays the match cards are subsequently taken off to be subjected to the further working stages.
- 5 With the aid of the hereinbefore described machine the method according to the invention is altogether automatically performable until the stock material on the winding device V is exhausted.
- 10 In the Figs. 3 to 7 the machine frame M constitutes for the main part a drying chamber and carries at its rear end the impregnating device J and at its front end the stamping device S. The supply rolls V for the webs of material to be worked are arranged below the impregnating device in the example illustrated in the number of twelve, and the arrangement is such that each two adjacent rolls are staggered in the longitudinal direction of the machine in order to provide the necessary space for their bearings. From the supply rolls the webs B pass to the impregnating device and from thence to the feed roll 1, a removably mounted counter roll 2 being provided for pressing the webs against this roll. The feed roll extends in one length the full width of the machine, whereas the counter roll is subdivided correspondingly to the number of webs. For mounting the counter roll, bell crank levers 3 are arranged on the machine frame the respective upwardly directed arm 4 of which is engaged by connecting rods 17.
- To the side plates of the machine, on the inside of the drying chamber, rails 5 of angular cross-section are connected on which link chains 6 are running, the respective links of which being interconnected by transverse trusses 7, thus forming a continuous conveyor band for carrying the webs B of material. For guiding these webs laterally, the trusses 7 are provided at regular intervals with small stirrups 9 which are spaced only the distance of a wooden web apart. The chains of the conveyor band are passed over end rollers 10, 11, the forward roller 10 being actuated by the main drive of the machine by the intermediary of a speed translation gear whereas from the shaft of the rear roller 11 of the feed roll 1 for the wooden webs is driven by means of a spur gear drive. The lower portion of the conveyor band is also guided on rails 5a of angular cross-section.
- On the shields of the machine bearing supports 12 are provided in which shafts 14 are mounted. On the outside of these supports on the shafts 14 levers are arranged, namely at the forward 55 pair of supports bell crank levers 15, 16 and at the rearward pair one armed levers 15', the downwardly directed arms 15, 15' at the two supports on one side of the machine being interconnected by the rod 17. This rod extends in 60 the path of the respective lever arm 4 as above-said by means of which the lever arms 3 carrying the counter rolls are rocked. The forwardly and obliquely upwardly extending arms 16 of the bell crank levers are engaged by a rod 18 which on its other end is linked to the free end of the one arm of a bell crank lever 19, the other end of which carries a roller engaging a cam disc Kb. On the inner side of the bearing supports the shafts of each pair of these supports 65 carry fixed laterally forwardly projecting arms 20 and between the two arms of each pair of bearing supports a supporting beam 21 of a square cross-section (Figs. 5 and 7) is arranged and on each beam twelve rod-shaped hangers 22 adjustably secured which are suspended exactly
- above the middle of the wooden webs B. To each pair of longitudinally lined up hangers a press-bar 23 is pivotally connected the rear end of which is bent upwardly in the manner of sledge-runners and which in the inoperative position rests against the wooden web B underneath so as to load the web for straightening or dressing purposes. In the forward bearing supports of the machine frame an axle 24 is mounted to which inner lever arms 25 are secured. The two levers of the pair of bearing supports are inter-connected by a rod 26 which bears on a nose 27 on each press-bar 23. Externally on the axle 24 an arm 28 is provided to which a rod 29 is connected, the other end of which is linked to a bell crank lever actuated by means of the cam disc Ka. When the rods 18 and 29 are moved by action of the related cam discs in the direction of the arrow, the arms 20 are swung upwardly, thus slightly raising the press-bars 23, whereupon the rocking motion of the arm 28 effects a rearward motion of the press-bars and thereby a further lifting of the same in the position shown in chain dotted lines in Fig. 7, the supporting beams 21 being correspondingly rocked about their journal pins.
- Ahead of the conveyor band the stamping device St is situated to which the wooden webs are fed directly from the forward roll 10 by means of the pair of feed rolls 30, 31.
- The operation of the described device is as follows:
- The feed rolls 1, 2 impart to the webs of material B a continuous advancing movement on the conveyor band, where they are loaded by the press-bars 23, towards the feed rolls 30, 31 which in turn convey the wooden webs intermittently to the stamping tool, whereby each time during the short period between stamping incidences the stamping tools 39, 41 stamp out a series of matches from each web. Each time the rolls 30, 31 impart an intermittent movement to the webs, a stretching of the webs results which is again equalized by the continuous rolling of rolls 1, 2. As soon as a number of matches corresponding to the width of a card is stamped out and cut off the press-bars 23 are retracted from the webs together with the counter feed roll 3 in the above-described manner, thus permitting the webs to equalize in length unhindered, since also the continuous advance movement is then stopped. Thereupon the retracted bars are again lowered and the stamping operation resumed.
- Owing to the described arrangement the wooden webs are laterally guided in exact manner and permitted to expand and shrink freely in periodical time intervals, so that the occurrence of occasional internal tensile stresses or warpings is prevented from causing irregularities in the stamping effect or even rupture.
- For a thorough understanding of the stamping device illustrated in the Figs. 8 to 16, Fig. 15 will serve to illustrate a match card stamped out from a wooden web including ten matches of the width b which represents at the same time the feed step of the intermittently advanced web. This figure shows plainly the slits t between the matches and the apertures l between the tips of the same which are produced by stamping out correspondingly shaped tongues of material. The definitely stamped card is cut off during the last stamping stroke along the line T by means of a separate cutting blade while the advancing movement is interrupted. Alternatively, as shown in Fig. 16, in a wider web of

material the tips of the matches may be stamped out at both longitudinal edges and then the web folded about a scored line L spaced from its centre line so that the match tips come to lie 5 in offset relation, as shown in dotted lines on the right hand side in this figure.

The stamping device is provided with two side shields 32 attached to the frame of the match-making-machine not shown in these figures, and 10 formed at their upper part with a vertical slot 32a for guiding the cross-piece 33 for holding the stamping tools. In the latter a number of tool holders 34a, equal to the number of the webs of material, in the present case twelve, are 15 vertically displaceably inserted, a set screw 35 screwed in the cross-piece for the tools from above serving as a stop member for each tool holder and a head screw 36a screwed in from the side as a fastening means. For moving the cross-piece 20 33 for the tools up and down connecting rods 37 are provided which act on pins on the cross-piece that project laterally through the side shields 32 and which are actuated by eccentrics 38 carried by the main drive shaft W. To the lower end of 25 each tool holder 34a a flat stamping blade 39 extending transversely of the web of material is screwed, the blade being provided with longitudinal slots for engaging connecting screws 39a, so as to permit of adjusting the blade to the required site height. The width of the stamping blade corresponds to the straight flange t of the matches. A plurality of separate tool holders 34b are mounted on the cross piece 33. These tool holders 34b are mounted laterally of the tool holders 34a and 30 are secured by means of screws 36b (Fig. 8). Punches 41 are linked to the tool holders 34b, which are pressed against the tools 39 by means of leaf springs 42. The punches 41 cooperate with recesses 53b of guide members 53 (Fig. 14) 35 to stamp out the apertures 1 of the match sheets. The cutting edge of this punch is of a cross-section as required for stamping out the apertures 1. In the downward direction the cutting edge of the punch projects considerably beyond 40 the stamping blade, so that the slit along the flangs t is only effected at the end of the stamping stroke, a slit t for the match flanks being stamped simultaneously with an aperture 1 for the preceding pair of matches.

Underneath the pair of feed rolls 30, 31 between the side shields 32 a supporting yoke U is arranged to the upper edge of which the bearing plate 40 is secured over which the webs B of material are passing. Below each web of material 45 a rectangular aperture 40a is provided in the bearing plate through which the counter roll 31 is adapted to bear against the web B of material, while the feed roll 30, which extends the full width of the machine and is provided above each 50 web of material with a ribbed circumference for driving engagement with this web, bears against the webs of material from above. The drive of the feed roll 30 is effected by means of a ratchet wheel 43 which cooperates with a pawl 43a which 55 is linked to an arm 44 and held in engagement with the ratchet wheel 43 by means of a tension spring 45 attached with one of its ends to the yoke U. The arm 44 is swingably arranged on a pin fixed on the side shield 32 and carries at its free 60 end a roller 46 which cooperates with a cam disc 47 on the main drive shaft W. The cam disc 47 effects via the ratchet wheel drive 43, 43a the required rotational displacement of the roll 30 for executing the feed after each down stroke of 65 the stamping tool. The rolls 10 are rotated con-

tinuously from the shaft W by means of link chains and spur gears, and the rolls drive the conveyor band 6 for bringing on the webs B of material. The counter roll 31 for each web of material is mounted in a sliding member 48 (Fig. 10) which is guided to be displaceable in the vertical direction in a vertical slot of the yoke U and pressed upwardly by means of a tension spring 49 attached with one of its ends to the yoke U, an adjusting nut 50 at the lower end of the sliding member serving for limiting the throw of the same.

For guiding the webs of material at the entrance to the feed rolls and the stamping device, guide ribs 51 are secured to the bearing plate 40, 80 between each two adjacent webs B of material. Forked guide tongues 52 (Figs. 10 and 13) are connected to ribs 51 and bear against the webs B of material and extend on both sides of the related guide ribs to the underside of the feed roll 95 30. Underneath each web of material to the rearward edge of the bearing plate a slightly downwardly deflected stirrup 56 is connected, which serves for guiding the web towards the upper side of the bearing plate 40 in case the web should 100 sag.

Each web of material is guided by a guide member 53 (Fig. 14) which is provided with a longitudinal slot 53a through which the web of material is passed and which, as aforesaid, is formed at one 105 end with the recess 53b, corresponding in cross-section exactly to the profile of the cutting edge of the punch, for guiding the latter. In front of the bearing plate 40 a vertical guide plate 54 is arranged and the stamping blade 39 is on one 110 side guided between an extension 55 of this guide plate and the front side flank of the guide member 53. The extension 55 is secured to the guide plate 54 by means of ribs 55a disposed in front of each stamping unit and serving at the same time for 115 guiding a holder 57 of the cutting blade 59 for serving a completed match card. The holder 57 is adjustably mounted in a sleeve 58, with its lower end (Fig. 10), the sleeve being pivotally mounted by means of a pivot pin 59a in a transverse tilting member 60. The tilting member 60 extends the full width of the machine frame and is revolvably mounted on journals 61. A tension spring 62 connected at one end to the tilting member 60 and at the other end to a lower extension 120 58a of the sleeve holds the cutting blade pressed against the guide plate 54. The tilting member 60 is provided with an arm 60a which extends in the downward direction in the path of a two-armed lever 63, 64. The latter is rotatably mounted 125 on a shaft 65 (Fig. 8) and its lower arm carries a roller 66 cooperating with a cam disc 67. A tension spring 68 anchored at one end in the machine frame maintains the roller 66 in bearing contact with the cam disc 67. On each full revolution of the cam disc 67, which is completed while the cross-piece with the tools performs ten working strokes, the double armed lever 63, 64 effects a rocking motion of the tilting member 60 and the latter a stroke of the cutting blade 59, whereby 130 the stamped match cards are severed along the line T in Fig. 16.

The Figs. 17 to 22 illustrate stacking devices for the reception of the definitely stamped match cards.

In the Figs. 17 and 18 the stamping device of the match-making machine is illustrated by showing all the parts that are necessary for a good understanding of the device. The stamping device, in which, as above-described, the completely 150

stamped match card B_1 is periodically severed by the cutting blade 59 from the web B of material intermittently advanced by the feed rolls 30, 31, is provided with side shields 32. At the front edge 5 of the side shields 32 in bearing brackets 32a' the shaft of a transmission drum 68 is mounted. The transmission drum is provided along its width with twelve sections corresponding to the number of webs of material to be worked and each 10 section is subdivided by sheet metal partitions in chambers each of which receives a severed match card B_1 . For moving the transmission drum a ratchet wheel drive is provided, a two armed lever 72, 73 being arranged on one of the side shields 15 32, the one arm 73 of which carries at its free end a guide roller engaging a cam disc 76, while to the other arm of the lever a pawl 71 is linked which cooperates with the ratchet wheel 70. A tension spring 74 attached at one end to the side shield 20 holds the roller on the arm 73 pressed against the related cam disc and the operating pawl 71 is maintained in engagement with the ratchet wheel 70 by means of a tension spring 75. Immediately 25 after each time a match card has been severed, the described ratchet mechanism turns the transmission drum through the extent of one unit of division so that the match cards of a transverse row, which in the mean time were advanced by the feed means for the webs again rendered operative, 30 are gripped by the drum and carried off in the direction of the arrow in Fig. 17. Underneath the transmission drum between the brackets 32b of the side shields twelve conveyor bands 77 are arranged which are passed over rollers 78, 79 and 35 the upper portions of which form together with the vertical longitudinal walls 80 twelve stacking trays for the match cards. Concentric with the circumference of the drum above the conveyor band a comb 81 is arranged, the tines of which 40 guide the match cards during their travel through the forward lower quadrant of the drum and which ends at a chute 82 to which the match cards pass over through slots 81a in the comb to slide down on the chute to the conveyor bands 77. 45 Through guide slots in the chute 82 pushers 83 project forwardly which are operatively connected to a reciprocating pusher holder 84 in the form of a bar and which by means of the reciprocating motion imparted thereto push the match cards 50 as they slide down in front of them forwardly so as to stand up against the stack S . The pusher bar 84 is carried by two levers 85 which are secured to a shaft 86 extending between the brackets 32b. To the shaft 86 is also connected a lever 87 55 which carries at its free end a roller cooperating with a cam disc 88, so that the lever 85 is periodically rocked and the pushers 83 advanced. On the shaft 86 is further carried a lever 89 to which a pawl 90 is linked which is held in engagement 60 with a ratchet wheel 92 secured to the shaft 78a of the roller 78 by a counterweight 91 and which effects the advance movement of the conveyor bands 77. Underneath each conveyor band 77 a plate 93 is arranged which serves as a support. 65 In the Figs. 20 to 22 a variant construction of the stacking device is illustrated. The stamping device shown in these figures inclusive of the cutting blades 59 is equal to that represented in the Fig. 20. In front of the cutting blades 59 70 twelve conveyor bands 95 are disposed, the rearward guide roller 96 of which is of a relatively small diameter to permit the bands to approach the cutting blades for receiving the severed match cards as closely as possible. The conveyor bands 95 which pass over a supporting plate 75

8 run on forward guide rollers 97 to deliver the severed match cards B_1 forwardly to the said forward guide roller. Ahead of these forward guide rollers which are mounted on brackets 32b, connected to the side shields 32, on a shaft 99 transfer levers 100 are fastened which are in the form of an arcuate portion 100a merging in an extension 100b, the bottom plate of the stacking trays 101 for the webs of material extending tangentially to the arcuate portion of the respective lever arm and the entrance ends of the trays being closed by a sliding plate 104 which is periodically lowered for the length of a match card. Each transfer lever 100 consists of two sheet metal parts which are connected to the shaft 99 on both sides of the related conveyor band or transmission roller 97 respectively. Moreover, on the shaft 99 a downwardly extending arm 102 is secured which for periodically rocking the shaft and the transfer lever is engaged by a connecting rod 103. Each sliding plate 104 is secured on an upstanding rod 105, the middle portion of which is offset to avoid interfering with the shaft 99. The rods 105 are connected to a common transverse bar 106 which is mounted in two levers 107 secured on a 100 shaft 108. For the purpose of reciprocating the slides 104 a periodic rocking motion is imparted to the shaft 108 by means of a lever 109 fixed on shaft 108 and pivotally connected to a connecting rod 110, a reciprocating motion being imparted to said rod by any suitable means not shown in the drawings. 105

The match cards brought on by a conveyor band 95 for one web of material slide over the forward guide roller 97 down on the transfer lever 100 in the position of the extension 100b of the same as indicated in chain dotted lines in Fig. 22. At the same time the slide 104 is lowered and immediately afterwards the arm 100 rocked to the left in this figure, thus showing the match 115 card in the stacking tray which it enters in upstanding position so as to line up with the other stacked cards in which position it is held by the slide 104 which was again raised in the mean time. In order to provide for a transfer of the 120 match cards entirely free of disturbances the rearward edge of the bottom of the stacking tray is downwardly deflected in an arc concentric with the shaft 99.

This arrangement offers the advantage that defective or cracked match cards are readily detected and removed, thus avoiding scrap among the delivered goods. 125

I claim:

1. In a machine for the production of sheets of 130 flat matches from webs of material, in combination, an impregnating and a stamping device for the webs, said devices disposed at the rear and the front end of the frame of the machine respectively, feed means for advancing the webs 135 from said impregnating device towards said stamping device, flexible conveyor members moving from said impregnating device towards said stamping device, supporting members arranged between said conveyor members for carrying said 140 webs in the manner of a conveyor band, guide means on said supporting members for laterally guiding said webs, a press-bar correlated to each web of material for loading the same and adapted to be periodically retracted therefrom, and means 145 for stopping said feed means when said press-bars are in retracted position.

2. In a machine for the production of sheets of 150 flat matches from webs of material, in combination, an impregnating and a stamping device for

- the webs, said devices disposed at the rear and the front end of the frame of the machine respectively, feed means for advancing the webs from said impregnating device towards said 5 stamping device, flexible conveyor members moving from said impregnating device towards said stamping device, and adapted for carrying said webs in the manner of a conveyor band, bearing supports arranged in pairs in opposite disposition 10 on the sides of the machine frame, a shaft extending between oppositely disposed bearing supports, levers non-rotatably mounted on said shafts, supporting beams revolvably accommodated by opposite levers, hangers adjustably connected to 15 said supporting beams above the paths of said webs, a press-bar for each web of material suspended in the hangers above the path of the respective web, connecting rods disposed between the levers of the same side of the machine, a linkage for actuating the levers on the forward pair of bearing supports, and means for driving said actuating means from the main drive of the machine. 20 3. In a machine for the production of sheets of flat matches from webs of material, in combination, an impregnating and a stamping device for the webs, said devices disposed at the rear and the front end of the frame of the machine respectively, feed means for advancing the webs from said impregnating device towards said stamping device, flexible conveyor members moving from said impregnating device towards said stamping device and adapted for carrying said webs in the manner of a conveyor band, bearing 25 supports arranged in pairs in opposite disposition 30 on the sides of the machine frame, a shaft extending between oppositely disposed bearing supports, levers non-rotatably mounted on said shafts, supporting beams revolvably accommodated by opposite levers, hangers adjustably connected to 35 said supporting beams above the paths of said webs, a press-bar for each web of material suspended in the hangers above the path of the respective web, noses disposed on said press bars, 40 connecting rods disposed between the levers of the same side of the machine, a linkage for actuating the levers on the forward pair of bearing supports, means for driving said actuating means from the main drive of the machine, a lower shaft 45 extending between said oppositely disposed bearing supports, lever arms carried by said lower shaft on the inside of the machine frame, a traverse extending between the outer ends of said lever arms and cooperating with said noses, arms 50 secured to said lower shafts on the outside of the machine frame, actuating rods for said arms, and cam means provided in the main drive of the machine for cooperation with said actuating rods and adapted to completely retract the press-bars 55 moved out of contact with the webs of material by said linkage. 60 4. In a machine for the production of sheets of flat matches from webs of material, in combination, an impregnating and a stamping device for the webs, said devices disposed at the rear and the front end of the frame of the machine respectively, feed means for advancing the webs from said impregnating device towards said stamping device, flexible conveyor members moving from said impregnating device towards said stamping device, and adapted for carrying said webs in the manner of a conveyor band, bearing supports arranged in pairs in opposite disposition on the sides of the machine frame, a shaft extending between oppositely disposed bearing supports, le- 65 vers non-rotatably mounted on said shafts, supporting beams revolvably accommodate by opposite levers, hangers adjustably connected to said supporting beams above the paths of said webs, a press-bar for each web of material suspended in the hangers above the path of the respective web, a feed roll adapted for continuously advancing the webs of material and arranged at the rear end of the machine, a counter roll disposed above said feed roll, bell crank levers rotatably accommodating said counter roll on the respective arms of the same, connecting rods interconnecting the other arms of said bell crank levers and said levers non-rotatably mounted on said shafts, and actuating arms on said supporting beams for periodically retracting said counter roll together with said press bars from said webs of material. 70 5. In a machine for the production of sheets of flat matches from webs of material comprising a stamping device, a stamping blade for each web of material adapted for effecting a straight slit between adjacent matches, a tool holder for each stamping blade, an adjustable connection between said tool holder and each stamping blade for individually adjusting said blades relatively to said tool holder, a punch of a trapezoidal cross-section and formed with a tapering cutting edge for stamping out an aperture between adjacent matches for forming the match tips, a separate tool holder for said punch, a pivotal connection between said punch and said separate tool holder, a guide member for said punch, and a leaf spring for pressing said punch on said guide member. 75 6. In a machine for the production of sheets of flat matches from webs of material, in combination, an impregnating and a stamping device for the webs, said devices disposed at the rear end and the front end of the frame of the machine respectively, feed means for advancing the webs from said impregnating device towards said stamping device, a ribbed feed roll included in said feed means behind the stamping position of said stamping device and adapted for intermittently feeding said webs to said stamping position, a counter roll for each web cooperating with said feed roll, a supporting yoke for the webs transversely disposed in the machine frame underneath said feed roll, an apertured bearing plate provided on top of said supporting yoke, a sliding member vertically displaceably arranged in said supporting yoke underneath the path of each web, mounting means provided on said sliding member for the respective counter roll, and a spring interposed between said yoke and each sliding member for urging the related counter roll through a correlated aperture in said bearing plate against the corresponding web of material for pressing said web against said feed roll. 80 7. In a machine for the production of sheets of flat matches from webs of material, in combination, an impregnating and a stamping device for the webs, said devices disposed at the rear end and the front end of the frame of the machine respectively, feed means for advancing the webs from said impregnating device towards said stamping device, a ribbed feed roll included in said feed means behind the stamping position of said stamping device and adapted for intermittently feeding said webs to said stamping position, a counter roll for each web cooperating with said feed roll, a supporting yoke for the webs transversely disposed in the machine frame underneath said feed roll, an apertured bearing 85 90 95 100 105 110 115 120 125 130 135 140 145 150

- plate provided on top of said supporting yoke, guide ribs arranged on said bearing plate for laterally guiding the webs of material, forked guide tongues straddling said guide ribs for holding the webs entering between said feed roll and said counter rolls, and means for yieldingly urging said counter rolls against said feed roll through the correlated apertures in said bearing plate for pressing the webs of material against said feed roll.
8. In a machine for the production of sheets of flat matches from webs of material, in combination, a stamping device for the matches, a bearing plate for the webs extending across the stamping position of said stamping device, a supporting yoke for said bearing plate, a guide plate provided in front of said bearing plate of said stamping device, and secured to said supporting yoke, a cutting blade for each web for severing a completed match sheet therefrom associated with said stamping device, a holder for said cutting blade, a tilting member extending across the full width of the machine frame, adjustable connecting means arranged between said holders and said tilting member adapting said cutting blades to be vertically adjusted and operatively connected with said tilting member, and a spring for each cutting blade cooperating with said adjustable connecting means between said holders and said tilting plate for pressing said cutting blades against said guide plate.
9. In a machine for the production of sheets of flat matches from webs of material, in combination, a stamping device for the matches, a bearing plate for the webs extending across the stamping position of said stamping device, a supporting yoke for said bearing plate, a guide plate provided in front of said bearing plate of said stamping device, and secured to said supporting yoke, a cutting blade for each web for severing a completed match sheet therefrom associated with said stamping device, a holder for said cutting blade, a tilting member extending across the full width of the machine frame, adjustable connecting means arranged between said holders and said tilting member adapting said cutting blades to be vertically adjusted and operatively connected with said tilting member, and a spring for each cutting blade cooperating with said adjustable connecting means between said holders and said tilting plate for pressing said cutting blades against said guide plate, an arm provided on said tilting member, a two armed lever operatively connected with said arm, and cam means cooperating with said two armed lever and adapted to periodically rock said tilting member upon the completion of a match sheet for severing the same from each web of material by said cutting blades.
10. In a machine for the production of sheets of flat matches from webs of material, in combination, a stamping device for the matches, a cutting blade for each web for severing the match sheets therefrom associated with said stamping device, a stacking device for the match sheets succeeding said stamping device, a transmission drum provided in said stacking device in front of said stamping device and subdivided along its width into a number of sections corresponding to the webs of material, chambers each for receiving a match sheet severed by said cutting blades and formed in the circumference of said sections of said transmission drum, a comb for guiding the match sheets contained in said chambers arranged opposite the delivery portion of
- the circumference of said drum, inclined chutes arranged at the delivery end of said comb, stacking trays for the match sheets adjoining said chutes, conveyor bands constituting the bottom of said stacking trays, pushers cooperating with said stacking trays for shoving the match sheets arriving from said chutes in an upright position into the same, and means for actuating said stacking device inclusive of said pushers in conjunction with said cutting blades severing the match sheets.
11. In a machine for the production of sheets of flat matches from webs of material, in combination, a stamping device for the matches, a cutting blade for each web for severing the match sheets therefrom associated with said stamping device, a stacking device for the match sheets succeeding said stamping device, a transmission drum provided in said stacking device in front of said stamping device and subdivided along its width into a number of sections corresponding to the webs of material, chambers each for receiving a match sheet severed by said cutting blades and formed in the circumference of said sections of said transmission drum, an escapement mechanism for actuating said transmission drum, a comb for guiding the match sheets contained in said chambers arranged opposite the delivery portion of the circumference of said drum, inclined chutes arranged at the delivery end of said comb, stacking trays for the match sheets adjoining said chutes, conveyor bands constituting the bottom of said stacking trays, another escapement mechanism for actuating said conveyor bands, a common actuating rod for said pushers, rockable levers accommodating said actuating rod, cam means for actuating said rockable levers, and driving means for actuating said escapement mechanisms and said cam means in timed relationship and in conjunction with said cutting blades severing the match sheets.
12. In a method for the production of sheets of flat matches from wood veneer, the steps of unwinding coiled webs of wood veneer, advancing the webs in the longitudinal direction of the same, impregnating the webs, drying the webs and simultaneously stretching the webs longitudinally, intermittently pressing the webs during the drying operation, and stamping match sheets out of said webs.
13. In a machine for the production of sheets of flat matches from webs of material, in combination, a plurality of supply rolls for accommodating a supply of the web-shaped stock material for the match sheets, said rolls disposed at the rear end of the frame of the machine, a stamping device for the webs at the front end of the frame of the machine, flexible conveyor members moving from said supply rolls towards said stamping device and adapted to carry said webs in the manner of a belt conveyor, and a drying chamber substantially enclosing said conveyor members for drying the webs during their passage from said supply rolls to said stamping device.
14. In a machine for the production of sheets of flat matches from webs of material, in combination, a stamping device for the matches, a cutting blade for each web for severing the match sheets therefrom associated with said stamping device, a stacking device for the match sheets succeeding said stamping device, a conveying member provided in said stacking device in front of said stamping device and adapted to successively receive the match sheets severed by said

- cutting blade, a stacking tray for the match sheets adjoining said conveying member, a pusher cooperating with said stacking tray for shoving the match sheets arriving from said conveying member into the same, and means for actuating said stacking device inclusive of said pusher in conjunction with said cutting blade severing the match sheets.
15. In a machine for the production of sheets of flat matches from webs of material, in combination, a stamping device for the matches, a cutting blade for each web for severing the match sheets therefrom associated with said stamping device, a stacking device for the match sheets succeeding said stamping device, a transmission drum provided in said stacking device in front of said stamping device and subdivided along its width into a number of sections corresponding to the webs of material, chambers each for receiving a match sheet severed by said cutting blades and formed in the circumference of said sections of said transmission drum, stacking trays for the match sheets adjoining the delivery portion of the circumference of said drum, and means for actuating said stacking device in conjunction with said cutting blades severing the match sheets.
16. In a machine for the production of sheets of flat matches from webs of material, in combination, an impregnating device for the webs, a device for drying the webs after their passage through said impregnating device, feed means at the rear end of the drying device for advancing the webs in the longitudinal direction thereof, means for periodically retracting said feed means from engagement with the webs of material, and a stamping device for stamping the match sheets out of said webs.
17. In a machine for the production of sheets of flat matches from webs of material, in combination, an impregnating device for the webs, a device for drying the webs after their passage through said impregnating device, continuously driven feed rolls at the rear end of said drying device for advancing the webs in the longitudinal direction thereof, counter rolls disposed opposite said feed rolls, means for periodically retracting said counter rolls from said webs of material, intermittently driven feed rolls for the webs at the front end of said drying device, and a stamping device for stamping the match sheets out of said webs.
18. In a machine for the production of sheets of flat matches from webs of material, in combination, an impregnating device for the webs, a device for drying the webs after their passage through said impregnating device, a stamping device for stamping the match sheets out of said webs in the definitely impregnated and dried condition of the material, means for supporting the webs during their passage through said drying device, a press device movable together with said webs for pressing the webs against said supporting means, and means for periodically retracting said press device from the webs.
